PROCESS OF AND APPARATUS FOR AERATING AND FEEDING LIQUID FUEL.

1,100,126.

Specification of Letters Patent.

Patented June 16, 1914.

Application filed August 14, 1911. Serial No. 644,045.

To all whom it may concern:

Be it known that we, SAMUEL J. EVA, HENRY P. GRAY, and JAMES R. CHRISTY, citizens of the United States, residing at 5 Oakland, in the county of Alameda and State of California, have invented new and useful Improvements in Processes of and Apparatus for Aerating and Feeding Liquid Fuel, of which the following is a 10 specification.

The object of the present invention is to provide an improved process of, and apparatus for, aerating liquid fuel, for use in internal combustion engines.

15 In the accompanying drawing, Figure 1 is a diagrammatic view of the apparatus; Fig. 2 is a vertical section of the aerating cylinder; Fig. 3 is a vertical section of the relief valve mechanism; Fig. 4 is an enlarged vertical section of the automatic fuel valve; Fig. 5 is a side view thereof.

Referring to the drawing, 1 indicates an aerating receptacle, which is here shown as cylindrical in form, having depending from 25 the lower end thereof, an oil supply receptacle 2 which is also cylindrical in form but smaller in diameter. Suitably secured in the upper head 3 of said receptacle 1 is centrally contained a union 4, through which 30 leads a vertical tube 5, the upper end of which tube is connected with a compressed air pipe 6, by means of which pipe 6 and tube 5 compressed air is conducted into the interior of said receptacle 1. The upper 35 end of said tube 5 fits tightly in the bushing, but the intermediate portion 7 thereof is reduced in diameter to form an annular conduit 8, which connects with a transverse conduit 9 in the union 4, which conduit 9 in turn connects with an oil pipe 10. Thus oil 40 is supplied to the annular conduit 8. The lowermost portion of the tube 5 is still further reduced in diameter, as shown at 11, and surrounding said portion 11 of the tube 45 5 is an annular valve 12, the upper portion of which is formed with a circular series of recesses 13, each of which is open at the upper end or at the top of said valve, and tapers downward to the lower end. Said 50 valve is normally pressed upward by a coiled spring 14 surrounding the tube 5 and compressed between a fixed collar 15 thereon and the lower end of said valve. When 55 fully pressed upward by said spring, the whole of said recesses 13 are completely

closed on the outside by the union 4. But when, owing to the pressure of liquid fuel passing from the pipe 10 into the annular conduit 8, the annular valve 12 is depressed against the force of said spring 14, small 60 portions, the size of which is dependent upon the degree of said pressure, of said recesses 13 pass below the lower end of the bore for said tube 5 in said union, which lower end flares outwardly, and then the 65 liquid fuel under great pressure escapes from said recesses, and is immediately atomized. When liquid fuel is thus sprayed into a receptacle containing compressed air under considerable pressure, and is allowed 70 to collect in the bottom of the receptacle, it is found that it is very strongly charged or saturated with air. Fuel thus charged drops from the bottom of said receptacle into the oil supply chamber 2, from the 75 lower end of which it is conveyed by a pipe 18 to the internal combustion engine, not shown. Fuel oil thus saturated with air is very effective for operating said engine, as it is then more readily mixed with air admitted into the combustion chamber of said engine.

It is important to prevent any possibility of the oil rising into the aerating receptacle 1. For this purpose there is provided an 85 overflow pipe 19, which is connected with the oil supply chamber at about the middle thereof, and the other end of which is connected to a vertical pipe 20, which conducts saturated compressed air to the compression 90 chambers of the engine and the upper end of which pipe 20 is supplied with compressed air from the receptacle 1 by a pipe 21 having within said receptacle a downwardly opening aperture 22. From this pipe 21 a pipe 95 23 leads to the upper casing section 24 of a relief device 25. The said device comprises upper and lower casing sections 24, 27, between which is clamped a diaphragm 28 having centrally connected thereto a 100 valve 29, having a valve stem 30 which slides in a guideway 31 in the upper section. Conduits 32 in said section 24 conduct compressed air from the compressed air pipe 23 to the chamber 33 above said diaphragm. 105 The lower casing section 27 connects with the lower end of the pipe 20, an upper portion of which is connected, as before explained, with the overflow pipe 19.

In the normal operation of the device, 110

should there be no oil in the pipe 20, the valve 29 will remain seated on its seat 35, but, if the oil rise in the oil supply receptacle and passes over by the overflow pipe 19 into 5 the pipe 20 and forms a column therein of sufficient height, so that the pressure of the under side of the diaphragm 28 is slightly greater than the pressure on the upper side thereof, together with the pressure upon the 10 part of the valve 29 in contact with its seat, then said valve 29 will be raised from its seat, and oil will then flow from the lower chamber 36 by a pipe 37 to a suitable oil reservoir, not shown, to be again supplied 15 to the aerating chamber and aerated in the manner already explained. We preferably form the overflow pipe 19 curved upward intermediate of its ends which extend horizontally. The object of giving the overflow 20 pipe this shape is in order that the oil, flowing downward on the wall of the chamber 2 may not be able to enter the overflow pipe 19, and this construction is especially important for marine engines in which the 25 overflow pipe 19 is constantly changing its level owing to the rocking of the ship. At suitable points above and below the connection of the pipe 19 with the chamber 2, we connect with said chamber 2 gage cocks 38 30 for ascertaining at any time whether the oil is at the level of said gage cocks. The bottom of the chamber 2 is connected to a suitable drain cock 39. The pipes 20 and 23 have valves 40 and 41, and are connected by 35 a pipe 42 having therein a valve 43, which, in the normal operation of the device is closed. When it is desired to close the valves 40, 41, the valve 43 is opened, in order that there may be no danger of rupturing the 40 diaphragm 28 by one of the valves 40, 41, being closed before the other.

We claim:—

1. In the art of preparing and feeding aerated liquid fuel, the process of continuously spraying by external pressure liquid fuel into an aerating chamber at the top, continuously supplying to said aerating chamber air under pressure greater than atmospheric, continuously drawing out from 45 said chamber, near the bottom thereof, the aerated liquid fuel at a rate not greater than that at which it is supplied thereto, and automatically removing from the liquid fuel so aerated any excess thereof above a predetermined amount.

2. In an apparatus of the character described, the combination of an aerating

chamber, means for supplying compressed air thereto, means for supplying liquid fuel under pressure thereto, a valve for resiliently 60 opposing said latter means and formed to cause said liquid fuel to pass the valve in the form of spray, and a liquid fuel supply receptacle connected with the bottom of said chamber.

3. In an apparatus of the character described, the combination of an aerating chamber, means for admitting compressed air to said chamber, means for conducting liquid fuel to said chamber, means for injecting said liquid fuel into said chamber in the form of spray, and a receptacle connected with the bottom of said chamber for containing the aerated liquid fuel.

4. In an apparatus of the character described, the combination of an aerating chamber, means for admitting compressed air to said chamber, means for conducting liquid fuel to said chamber, means for injecting said liquid fuel into said chamber 70 in the form of spray, a receptacle connected with the bottom of said chamber for containing the aerated liquid fuel, an overflow pipe from said receptacle, a relief valve for permitting the escape of oil passed through said overflow pipe, and means controlled by the amount of oil so passed for actuating said valve.

5. In an apparatus of the character described, the combination of an aerating chamber, means for admitting compressed air to said chamber, means for conducting liquid fuel to said chamber, means for injecting said liquid fuel into said chamber in the form of spray, a receptacle connected 90 with the bottom of said chamber for containing the aerated liquid fuel, an overflow pipe from said receptacle, a relief valve for permitting the escape of oil passed through said overflow pipe, and means for operating 100 said valve adapted to be actuated in one direction by the pressure of the compressed air in the aerating chamber, and in the other direction by said pressure added to the pressure of a column of oil in the overflow pipe. 105

In testimony whereof we have hereunto set our hands in the presence of two subscribing witnesses.
